UNITED STATES PATENT OFFICE.

GEORGE H. JANES, OF PHILADELPHIA, PENNSYLVANIA.

DESIGN FOR A VASE.

42,628.

Specification for Design.

Patented June 18, 1912.

Application filed April 13, 1912. Serial No. 690,610. Term of patent 7 years.

To all whom it may concern:

Be it known that I, GEORGE H. JANES, a subject of the King of Great Britain, residing at West Philadelphia, in the county of Philadelphia and State of Pennsylvania, have invented a new, original, and ornamental Design for Vases, of which the following is a specification, reference being had to the accompanying drawing, forming part thereof.

The figure is a perspective view of a vase, showing my new design.

I claim:

The ornamental design for a vase, as shown.

GEORGE H. JANES.

Witnesses:

VICTORIA WAUGH,
ELIZABETH M. HUNT.
